UNITED STATES PATENT OFFICE

133,665

DESIGN FOR A COMBINED FAN STAND AND FAN

Alfred F. Fukal, Cincinnati, Ohio, assignor to William W. Welch, Cincinnati, Ohio

Application September 19, 1941, Serial No. 103,414

Term of patent 14 years

To all whom it may concern:

Be it known that I, Alfred F. Fukal, a citizen of the United States, residing at Cincinnati, in the county of Hamilton and State of Ohio, have invented a new, original, and ornamental Design for a Combined Fan Stand and Fan, of which the following is a specification, reference being had to the accompanying drawing, forming a part thereof.

The combined fan stand and fan is symmetrical about its vertical axis.

The characteristic features of my design reside in the portions shown in full lines.

I claim:

The ornamental design for a combined fan stand and fan, as shown and described.

ALFRED F. FUKAL.
